UNITED STATES PATENT OFFICE.

JOSEPH POSTERNOCK, OF WALPOLE, MASSACHUSETTS.

CLAMP-BUCKLE.

1,384,776.

Specification of Letters Patent. Patented July 19, 1921.

Application filed February 19, 1921. Serial No. 446,432.

To all whom it may concern:

Be it known that I, JOSEPH POSTERNOCK, a citizen of the United States, and resident of Walpole, in the county of Norfolk and 5 State of Massachusetts, have invented an Improvement in Clamp-Buckles, of which the following description, in connection with the accompanying drawings, is a specification, like letters on the drawings representing like parts.

My present invention relates to clamp buckles, belt connectors, and the like, and more particularly to a device of this character capable of connecting the ends of a 15 belt, or analogous structure, passing over pulleys.

In the manufacture of brake lining, it is the practice to make the same in various lengths and to then pass these lengths of 20 lining through a treating bath in the further process of manufacturing. The length of lining is run over pulleys, the treating bath being located intermediate such pulleys, and due primarily to the relatively 25 great length of the lining, the said lining is subjected to considerable tension by the pulleys, so much so that heretofore it has been necessary to overlap the ends of the brake lining about four inches and rivet 30 the ends together. As these riveted ends cannot be made usable when thus riveted together, they are waste and must be cut off the finished product. As these ends represent considerable outlay of money, it is de- 35 sirable that means be devised for saving them, and as the only possible way of doing this is to eliminate the necessity for overlapping, various devices have been proposed for temporarily holding the ends together without overlapping and without 40 rivets. Such devices have included various forms of commercial belt clasps and buckles, all of which have failed. The principal cause of such failures appears to 45 be the inability of the devices to hold the ends of the brake lining in position against the tension of the lining when the same is in motion, and particularly as the buckle or clasp passes over the pulleys.

With a view to obviating the objections of 50 this class of devices, as above pointed out, and to devise a connecting device that will perform the function of holding the ends of the belt or brake lining against tension and 55 at the same time make it possible for the clasp or buckle to pass readily over a pul-

ley, I have devised the subject matter of the present invention.

The principal object of my invention therefore, is an improved form of clamp 60 buckle or connector capable of holding the ends of a belt together when such belt is subjected to tension, and traveling over pulleys.

Another object is an improved device of 65 this character which will allow the same to pass readily over and around a pulley without letting go the ends of the belt or lining.

Other objects and novel features of construction and arrangements of parts will appear as the description of the invention 70 progresses.

In the accompanying drawing illustrating 75 the preferred embodiment of my invention,

Figure 1 is a top plan view,

Fig. 2 is a central longitudinal section of the same,

Fig. 3 is a bottom plan view, and

Fig. 4 is a sectional view on the line 4—4 80 of Fig. 1 looking in the direction of the arrows.

Referring to the drawing, 10 and 11 designate bars having their ends 12, 13 and 14, 15 respectively, bent up at right angles, to 85 form substantially U-shaped members, said ends being cut away to form coöperating hinge members 16 and 17. Slidably mounted on the ends 12, 13 and 14, 15 are members composed of a plate 18, provided with teeth 19, extensions 20 at the ends of said plate 18 being folded about the ends 12, 13 and 14, 15, as clearly shown in the drawings. The teeth 19 lie in a plane making an angle with the plate 18, the teeth being long 95 enough to engage with the bars 10 and 11, as clearly shown in Fig. 2. A bar 21, separated from and lying parallel to the plate 18, at the side remote from the teeth 19, is connected to said plate in any suitable manner, while an angular plate 22, also separated from and lying parallel to the plate, 18, adjacent the teeth 19, is connected to the plate 18 in any suitable manner.

To operate my improved device, the end 105 of the brake lining or belt 23 is passed up through or between the angular plate 22 and the bar 10—or 11—, then downward between the bar 10—or 11— and the teeth 19, then upward between the plate 18 and bar 21. The plate 18 is now forced toward the bar 10—or 11—, when the teeth 19 will 110

grip the brake lining or belt, the bar 10—or 11—assisting in this gripping operation. Any tension of the lining or belt 23 only serves to cause a tighter grip to be taken 5 thereon, and the hinges 16 and 17 allow the clamp buckle to articulate, making it possible to have the lining or belt flex around the pulley without altering the line of pull of the belt with respect to the gripping 10 members to such an extent as to cause a loosening of the belt in the clamp.

While I have described the preferred embodiment of my invention somewhat in detail, it is to be understood that I may vary 15 the size, shape and arrangement of parts constituting my device within wide limits without departing from the spirit of the invention. My clamp is strong, very economically made, will wear a relatively long 20 time, can be quickly disengaged and does not injure the ends of the fabric or lining. No waste part is lost or removed. My clamp buckle being open does not prevent any part of the belt ends from being treated 25 and therefore these end portions are usable. The clamping and buckle portions are so

constructed and arranged that the traveling of the belt around a pulley does not dislodge, loosen or disengage the clamping parts, but maintains the tightening grip secured by my device. The clamp buckle can be readily stamped out of stock material and therefore can be manufactured economically, while maintaining its strength and serviceability. 30 35

My invention is further defined in the form of claim as follows:

A clamp buckle comprising a pair of substantially U-shaped members hinged together to form a substantially rectangular articulated frame, a toothed plate slidably mounted on said members, and having the teeth adapted to engage with the cross bars of said U-shaped members, an angular guiding plate for each toothed plate lying 45 parallel to said teeth and on the opposite side of the said cross bars, and a bar parallel to each of said guiding plates and on the opposite side of said teeth. 40

In testimony whereof I have signed my 50 name to this specification.

J. POSTERNOCK.
